UNITED STATES PATENT OFFICE.

MALVIN LICHTER, OF NEW YORK, N. Y.

METHOD OF PREPARING PLATES FOR PRINTING.

1,348,019.

Specification of Letters Patent.

Patented July 27, 1920.

Application filed October 23, 1919. Serial No. 332,695.

To all whom it may concern:

Be it known that I, MALVIN LICHTER, a citizen of the United States, residing at New York city, county of New York, and

5 State of New York, have invented certain new and useful Improvements in Methods of Preparing Plates for Printing, of which the following is a full, clear, and concise description.

10 My invention relates to printing, and more especially to the production of printing plates—that is, plates provided with typographical surfaces and used in printing presses of various kinds, for the purpose of being alternately inked and impressed against blank sheets of paper, thus producing printed matter in a manner well understood in this art.

20 More particularly stated, my invention comprehends the production of printing plates by the use of a typewriting machine in connection with some process, for instance a photolithographic process or a plate engraving process, in such manner as 25 to avoid all necessity for type setting and distributing, but in which the lines of typographical characters are of uniform length, and as a consequence the printed lines made by impression of the plate upon paper are 30 likewise of uniform length.

Heretofore in this art printing plates have been made from typewritten original sheets, but in such cases the lines of typographical characters carried by the plate 35 were of different lengths, for the simple reason that the typewritten lines of the original sheet were not uniform in length.

What I seek primarily to do, therefore, is to produce a typewritten original sheet 40 upon which the lines are of uniform length, and then to make from this original sheet a printing plate the lines of which will of course be of the same proportionate dimensions as those of the original sheet and must 45 necessarily therefore be of uniform length.

Further, I seek to facilitate the work of the typist in spacing the words of each line of the original typewritten sheet, so as to render the lines thereof uniform in length.

50 Again, I seek to facilitate the proper spacing of the words in the different lines of the original typewritten copy sheet in order that the lines of the original typewritten sheet shall be of a common length.

55 Reference is made to the accompanying drawing forming a part of this specification

and in which like reference characters indicate like parts throughout the several figures.

Figure 1 is a fragmentary plan view of 60 the trial sheet which in one form of my invention is to be used as a guide, and then discarded.

Fig. 2 is a fragmentary plan view of an 65 original typewritten sheet to be used as a copy from which the plate is to be made, the sheet being made by aid of the trial sheet shown in Fig. 1, or not, as desired.

Fig. 3 is a plan view showing fragmentarily a printing plate made from the original 70 sheet appearing in Fig. 2, and for this purpose serving as copy.

The trial sheet, which I preferably use in many instances but which is not always essential, is shown fragmentarily in Fig. 1. 75 This trial sheet is usually prepared under the direction of the publisher, but may by special arrangement or otherwise be made by any person capable of operating an ordinary typewriting machine. A sheet of 80 paper *a* has typewritten upon it the matter *b*, consisting of words formed into lines, the lines ending in numerals, as shown at the right of this figure. Except for these numerals, which are merely super-added to the 85 lines, the typewriting does not differ from typewriting as ordinarily done. The manner in which the numerals are added is quite simple. As soon as the words of a line are completed, the typist merely adds, at the end 90 of the line, enough numerals in the successive order 1, 2, 3, 4, 5, etc., to render the line of a predetermined standard length, this being the length of the longest line which could be written upon the typewrit- 95 ing machine without changing the adjustment thereof. For instance according to Fig. 1 the maximum length of a line would be the width of fifty seven letters (and spaces equal to letters) in width. The first 100 or top line shown in Fig. 1 is, as to its wording, short of this maximum length by the space required for two letters or numerals; hence the typist, after writing the last word of the line, to wit, the word 105 States, forthwith begins putting in numerals beginning with the numeral 1, and as soon as two numerals are thus added the line is brought up to the standard length. Similarly the second line has enough numerals added upon its end to bring it up to 110 the maximum or standard length, four nu-

merals being required for this purpose and they being of course 1, 2, 3, 4. The other lines are similarly treated, each line receiving enough numerals to bring its length up to the maximum.

When this step is completed, it will be noted that each line carries its own index for disclosing the extent to which the wording of the line is short of the maximum or standard length of line above mentioned. Indeed the typist need not count the numerals at the ends of the lines but can merely glance at the last or final numeral in each line, in order to determine the shortage of the line, considered as to its wording alone, as compared with the said standard length of line. For instance the bottom line shown in this figure ends with the numeral 3, indicating that the wording of this line is short by three spaces, or by a space equal to that occupied by three letters. The next to the last line ends with the numeral 4, indicating that the wording of this line is short by the space of four letters.

Thus when the trial sheet shown in Fig. 1 is completed, it carries its own graphic symbols indicating the respective shortages in the length of the several lines. Hence the trial sheet shows on its face all of the data needed by the typist in order to enable the latter to typewrite a second sheet, corresponding line for line with the sheet shown in Fig. 1, but with the numerals omitted and with the spacing of the words distributed differently than that shown in Fig. 1, so that the words alone will fill all of the lines out to the maximum length, as shown in Fig. 2. This done the sheet shown in Fig. 1, and which I designate as the trial sheet, may be discarded altogether or at least filed away for future reference and has nothing to do with the further steps of my method.

The new sheet made up as just described and shown in Fig. 2 differs from the trial sheet in no other respect than in the length of the lines, the spacing of the words to obtain the length of the lines, and the omission of the numerals. The new sheet thus made and shown in Fig. 2 I designate as the original typewritten sheet, because in subsequent operations it is to be treated as an original as the term is used in this art.

From the sheet of the kind indicated in Fig. 2 and consisting of the paper sheet *c*

carrying typewritten lines *d* of uniform length, a plate is made as shown in Fig. 3. This plate consists of a flat body member *e* provided with typographical characters *f*. The plate may be made by any process well known in this art, as for instance the photolithographic process or the photoengraving process. The plate may be reduced or enlarged in size as compared with the original, and the typographical characters may be made either in relief or in intaglio, or may have any other characteristic which in this art can be conferred upon a printing plate.

The printing plate being completed, it is placed upon a printing press in the manner well known in this art, and is alternately inked and pressed against sheets of paper, so as to produce printed matter in any desired quantity.

I do not limit myself to each and every detail of my method as above described, nor to the identical structure of the articles of manufacture illustrated and described at length, the scope of my invention being commensurate with my claims.

I claim—

1. The method, herein described, of making a printing plate, which consists in preparing a typewritten sheet having intelligible characters arranged in lines of different lengths and providing means thereon for indicating differences in the lengths of said lines, copying upon a second sheet lines coinciding in subject matter with said first mentioned lines but of uniform length, and making a printing plate from said second mentioned sheet.

2. The method, herein described, of making a printing plate, which consists in typewriting a sheet so as to exhibit words arranged into lines varying slightly in length and also to exhibit graphic symbols indicating differences in the lengths of the respective lines, preparing a second sheet exhibiting said words arranged to run line for line with said first mentioned sheet, said second sheet being free of said graphic symbols but having its words so spaced apart as to equalize the differences indicated by said graphic symbols, so that the lines of said second sheet are of a common length, and making a printing plate from said second sheet.

MALVIN LICHTER.
